Attorney

UNITED STATES PATENT OFFICE.

ROBERT G. DRAY, OF SAVANNAH, MISSOURI.

SHIRT.

Application filed August 18, 1925. Serial No. 51,053.

This invention relates broadly to wearing apparel and has particular reference to a top shirt to be worn by men and boys, although it is not to be restricted to this particular use.

The principal feature of the improved shirt is a detachable and reversible collar, either side of which may be turned out so that when one side becomes soiled, the other side may be brought into use to give double wear.

Briefly, the invention relates to a slit neck band forming a pocket for reception of the lower edge of the detachable collar, together with buttons or their equivalents for maintaining the collar in position.

In the accompanying drawings forming a part of this application, and in which like numerals are employed to designate like parts throughout the same:

Fig. 1 is a perspective view of a portion of a shirt constructed in accordance with the present invention.

Fig. 2 is an elevation of the collar detailed.

Fig. 3 is a section through the collar and neck band of the shirt showing the manner in which the collar is attached.

Referring to the drawings in detail, the reference character 1 designates the body portion of the shirt and 2 designates the neck band generally. In the present instance, the neck band is formed from inner and outer sections 3 and 4 respectively. The edge portions of these sections are stitched or otherwise connected together to form a pocket for reception of the detachable collar 5. The collar as better shown in Fig. 2, has a curved lower edge imparting the desired shape thereto and along this edge it is provided with longitudinally extending button holes 6 reinforced in the customary manner. In this connection, it will be noted that the inner section 3 of the neck band is provided with a plurality of buttons 7 which are stitched at 8 to the same, and the outer section 4 is provided with button holes for cooperation with these buttons.

It is also obvious that the button holes 6 in the collar are intended to be connected with the buttons and are therefore arranged at the proper intervals to register with the button holes in the outer section 4 of the neck band. It will be noted that the neck band is provided with the customary exten-

sion 9 which is formed with a single button hole extending entirely therethrough and this is adapted to be connected with the endmost button on the left hand end of the neck band.

This particular button is therefore given a double function serving to connect the ends of the band together and for attaching the adjacent ends of the collar in place.

In practice, the adjacent faces of the two sections of the neck band are faced with a thin ply of material to prevent the occurrence of raw edges and to resist wear. These neck band sections must be rather thin so that the neck band will not be unusually bulky or sufficiently thick to render it uncomfortable.

From the foregoing description and drawings it will be seen that I have evolved and produced a novel top shirt having a sectional neck band constructed to provide a pocket for reception of the bottom edge of a reversible collar, the neck band being provided with buttons and button holes for cooperation with button holes on the collar, for detachably holding the collar in place, and allowing it to be readily reversed so as to dispose either face outwardly.

Accordingly, a double wear collar is provided, and when one side gets soiled, the other side may be brought into play so as to give longer use. The actual shirt, however, has the appearance of the customary soft shirt worn with a permanently attached collar. The buttons are hidden from view and do not detract in any way from the neat appearance which the shirt has.

While the preferred embodiment of the invention has been shown and described, it is to be understood that minor changes coming within the field of invention claimed may be resorted to if desired.

Having thus described my invention, what I claim as new is:

A shirt provided with a neck band composed of inner and outer sections, said sections being stitched together at their lower edges to the shirt, and extending from one of the forward edges of the shirt to a point beyond the other forward edge whereby to form a tab, the upper edges of the tab forming portion of the neck band being stitched together, the neck band being open at its upper edge to provide a pocket for the reception of a collar, buttons carried by the inner

section of the neck band, the outer section being provided with button holes directly opposite said buttons, the tab portion of the neck band being provided with a through button hole adapted for cooperation with a button on the opposite side portion of the neck band when the neck band is closed, and a separable and reversible collar insertable in said pocket and provided with button holes for cooperation with the first mentioned buttonholes and buttons. 10

In testimony whereof I affix my signature.

ROBERT G. DRAY.
